UNITED STATES PATENT OFFICE.

EDUARD GROSSE, OF WACHWITZ, NEAR DRESDEN, GERMANY.

PRINTING MACHINE.

Application filed May 5, 1921. Serial No. 467,187.

(GRANTED UNDER THE PROVISIONS OF THE ACT OF MARCH 3, 1921, 41 STAT. L., 1313.)

To all whom it may concern:

Be it known that I, EDUARD GROSSE, a subject of Germany, and citizen of the Republic of Germany, residing at Wachwitz, 5 near Dresden, Germany, Grundstr. 8, have invented certain new and useful Improvements in Printing Machines (for which I have filed applications in Germany, as follows: G 46353 XII/15d, filed March 6, 1918, 10 Patent #376,781, and Germany, G 47444/XII/15d, filed November 29, 1918, Patent #377,595), of which the following is a specification.

The present invention relates to a platen printing press of the known type, wherein the hard surface of the platen is directly brought onto the hard surface of the setting plate in order to perform the printing action which, as may be easily understood cannot 15 be done without a very high pressure so that a very strongly built machine must be used and even then the production of large sheets in producing auto-types is difficult and consists in the combination, construction and arrangement of parts herein described, having 20 the purpose of reducing the necessary pressure.

With these and other objects in view, the invention consists in a device which may or 25 may not be used in respective circumstances according to which the pressure of the platen will not act directly upon the hard surface of the setting plate, but effects a primary print which by means of a roller is transmitted upon an elastic flat form, onto which the platen carrying the working sheet is 30 pressed. The operation with this elastic form requires but very little pressure even in the production of large sheets and allows 35 the printing machine to be lightly built, and moreover said arrangement permits the printing of two colored prints in one stroke.

The accompanying drawings represent 40 some different forms of the present invention and the way of applying the same in different printing machines.

Fig. 1 is a section through the first form 45 of execution of the present invention,

Fig. 2 is a detail view,

Fig. 3 is a diagrammatic view of a toggle-joint-lever press with the rotating roller system according to Fig. 1.

As may be seen from the drawings, Fig. 1 shows the present invention as adapted to

a platen press in which the paint-applying and transmitting rollers are arranged to be rotated round the middle-portion of the press, so that a quiet and even movement is obtained.

The numeral 1 indicates the casing of the platen press, 2 and 3 are disks which are arranged in the middle-portion of the press, and 4 is an endless metal band, running over said disks 2 and 3. The paint-applying rollers 5, 5 and the transmission roller 6 are arranged on said metal band and adapted to rotate therewith round the middle-portion of the press. The said endless band 4 is driven by the spur gears 7 and 8, the latter of which is mounted upon the main shaft 9 of the printing press. Said main shaft carries the crank 10 adapted to transmit a to-and-fro movement from shaft 9 to the platen 11. It is understood that during each to-and-fro movement of the platen the spur gear 8 will complete one rotation. As the spur gear 8 engages the spur gear 7, which is half as large as the gear 8 and mounted on the same shaft 12 as the disk 2 which carries the metal band 4, the spur gear 7 and the disks 2 will complete two rotations during each rotation of the spur gear 8 and each to-and-fro movement of the platen 11, so that the endless metal band 4, which is twice as long as the periphery of the disk 2, will be guided once round the middle portion of the press during one to-and-fro movement of the platen. This is due to the difference in size of the spur gears 7 and 8. As the paint-applying-rollers and the transmission roller 90 are fixed on said metal band the same will also be carried once round the middle-portion of the press during one to-and-fro movement of the platen 11.

13 is the setting plate and 14 the flat form. 95 15 is the paint-roller which is adapted to rotate in an opposite sense to the paint-applying-rollers, in order to enable the latter to take up ample and well distributed paint, which they may carry over to the printing forms. 16 are teeth provided at the periphery of the transmission roller and adapted to engage a rack 17 arranged round the middle portion of the printing press. 100 18, 18 are movable roller-carriers, in which the rollers 5, 5 for applying the paint and the transmission roller 6 are rotatably mounted. Said roller-carriers are guided 105

by means of a guide-piece 19 wherein the said roller-carriers 18, 18 are held by means of small rollers 20, 20 and 21 as shown in Fig. 2, or other suitable means may be employed.

The paint-roller which supplies paint to the paint-applying-rollers 5, 5 consists of the paint-roller 15 which is driven by means of the spur gear 22 fixed to the latter 10 by means of an intermediate wheel 23 driven from the wheel 8 and the distributing rollers 24, 25, 26 and 27, which are supplied with paint by roller 28 from the roller 29 of the paint-reservoir.

15 The above described machine operates as follows:—

The setting plate 13 is shown in its position at the back of the machine, the flat form 14 being arranged on the same side 20 with the platen 11, the press being represented in its printing position.

The platen 11 is adapted to press against the flat form 14 and the paint-applying-rollers 5, 5 are run over the paint-roller 15 25 and take up paint.

If in continuation of the movement, the platen 11 passes from its printing position into the position for receiving the working sheets, the endless metal band 4 moves on 30 with its rollers 5, 5 and 6 in the direction of the arrow, so that the rollers 5, 5 are run over the setting form 13 and provide the same with paint.

Thereafter the rollers are guided round 35 the lower part of the platen printing press and pass forward over the form while the platen is in open or retracted position. Said paint-applying-rollers may be somewhat raised by any means in order to prevent 40 touching the flat form. The transmission-roller 6 however which is rotated by the rack 17 moves over the flat form 14 and transmits thereto the picture, which it has received from the setting plate 13 in passing 45 the same.

Thereafter the rollers are moved around the disks 30 and over the paint-roller 15, while the platen 11 moves to printing position so that the print upon the flat form 14 50 will be printed on the working sheet upon the platen 11.

It will be understood that the printing action will be performed as follows:—

The transmission roller 6 takes up the 55 negative picture from the setting form 13 having been previously provided with paint. On the roller 6 the picture is a positive one. Said roller transmits this positive picture to the elastic flat form 14, as hereinbefore stated, and hence forms a negative picture thereon, which produces a positive picture upon the working sheet lying upon the platen 11. The transmission roller being rotated by the rack 17 in order to obtain a

sharp imprint, may besides be provided with 65 little rollers adapted to be guided in respective guides, which may be raised or lowered in respect of the length of the forms 13 and 14. The spring-controlled paint-applying-rollers 5, 5 are as well guided in adjustable guides by mean of respective rollers.

It is evident that two or more sets of paint-applying-rollers as well as two transmission rollers may be provided. This may be done in applying the second set of rollers at the opposite side of the metal band 4. In this event there must be a toothed wheel and a gear which in each rotation of the spur gear 8 effects but one rotation of the disk 31. As the metal band 4 is twice as 75 long as the periphery of the disk 31 the rollers 5, 5 and 6 will in this form of execution complete but one half rotation during one to-and-fro movement, so that the oppositely arranged rollers will be alternately caused 80 to pass between the platen 11 and the flat form 14, and a quick movement of the platen is combined with a slow movement of the paint-applying-rollers and the transmission 85 rollers.

Having now particularly described the nature of my said invention and in what manner the same is to be performed, I declare, that what I claim is:—

1. In improvements in platen-printing machines, a platen, a setting plate and an elastic flat form, paint-rollers, paint-applying-rollers and a transmission roller, an endless band carrying both said paint-applying-rollers and said transmission roller 100 around the middle-portion of the printing press, disks in the upper and lower part of said middle-portion of the printing press for guiding said band, means for rotating said disks with said carrying means and means for moving said platen, each driving means cooperating with the other in such a manner as to accommodate the rotation of the carrying means around the middle-portion of the printing press, to the to-and-fro- 105 movement of the platen, substantially as described.

2. In improvements in platen-printing machines, a platen, a setting plate and an elastic flat form arranged around the middle portion of the printing press, paint-rollers, paint-applying-rollers and a transmission roller and an endless band carrying said paint-applying-rollers and transmission roller, a rack provided around the middle-portion of the printing press, teeth provided at the periphery of said transmission roller being adapted to engage said rack in order to obtain an exact print on said transmission roller when passing over said setting plate, 115 substantially as described.

In testimony whereof I affix my signature.
EDUARD GROSSE.
